UNITED STATES PATENT OFFICE.

WALTER L. CONWELL, OF MONTCLAIR, NEW JERSEY, ASSIGNOR TO ELLCON COMPANY, OF NEW YORK, N. Y., A CORPORATION OF NEW YORK.

METALLIC DOOR.

1,270,012.

Specification of Letters Patent. Patented June 18, 1918.

Application filed December 4, 1914. Serial No. 875,483.

To all whom it may concern:

Be it known that I, WALTER L. CONWELL, residing at Montclair, N. J., and being a citizen of the United States, have invented 5 certain new and useful Improvements in Metallic Doors, of which the following is a full, clear, and exact description, such as will enable others skilled in the art to which it appertains to make and to use the same, 10 reference being had to the accompanying drawings, which illustrate the preferred form of the invention, though it is to be understood that the invention is not limited to the exact details of construction shown and 15 described, as it is obvious that various modifications thereof will occur to persons skilled in the art.

In said drawings:

Figure 1 is a side elevation of the door. 20 Fig. 2 is a similar view on an enlarged scale, intermediate vertical and horizontal portions being broken out.

Fig. 3 is an enlarged section through the top rail of the door, taken on line 3—3, of 25 Fig. 1, and looking in the direction of the arrows.

Fig. 4 is also an enlarged transverse section, but is taken through the intermediate rail, on line 4—4, of the same figure, and is 30 viewed in the same direction.

Fig. 5 is another enlarged transverse section taken through the bottom rail of the door on line 5—5, of Fig. 1.

Fig. 6 is a view similar to Fig. 3, but is 35 taken on line 6—6, of Fig. 1, looking in the opposite direction.

Fig. 7 is a horizontal section through a portion of the top rail of the door and its curtain pocket, being taken on line 7—7, of 40 Fig. 2.

Fig. 8 is another horizontal section and is taken on line 8—8, of Fig. 2 in a lower plane and through one of the stiles; and

Fig. 9 is an end elevation of a portion of 45 the inner edge of the door, showing the application of one of the hinges.

The modern tendency toward the use of 50 steel and other metals in the architectural, car building and other structural industries has presented among other problems the production of doors constructed of such materials, which shall be of comparatively simple design, requisite strength, durability and pleasing appearance, combined with all the

advantages developed in the wooden doors 55 throughout their period of predominance.

With these ends in view, I have devised my present invention, and have had among other objects the purpose of providing one of the parts of a door with a shade pocket 60 adapted to diminish the protrusion of any shade or curtain applied to the side of the door.

Another object is the provision of coöperating guides for the free portion of such 65 shade or curtain, and it is within the comprehension of the invention to have such guides coact with said pocket to inclose either the ends or the entire rolled portion of the shade, and to furnish bearings or 70 bearing attachment means for the shade roller.

Means for the application of hinges have been devised which permit of the countersinking of the applied leaves thereof in the 75 manner approved for well finished doors, and avoid the imposition of inordinate stresses to parts of the door least capable of withstanding them.

The door edge-outlining and panel-opening frames, the removable panel and the means for holding, cushioning and retaining the same, and also the form of the complementary door edge strips of the door illustrated are, except for the omission of certain types of the latter, similar to the corresponding parts of the doors illustrated in an application for slidable metallic doors, filed by me contemporaneously herewith, there being, however, some new relationships.

Unenumerated advantages becoming apparent hereinafter obviously come within the scope of this invention, and are to be regarded as so doing.

With particular reference to the drawings, 1 and 2 represent door side sheets on opposite sides of the door, preferably having upper panel openings and being pressed to simulate the stiles 3, top rail 4, intermediate 100 rail 5 and bottom rail 6, of a conventional type of door. The number of panels may be governed by the number of the rails, and mullions may be introduced in a like manner, if desired. Door sheet 2 may have one 105 or more integral simulated panels 7, while door sheet 1 is depicted as having a lower panel opening registering with the integral

panel 7 of sheet 2, and having flanges 8 lapping and welded or otherwise secured to said integral panel.

Between, spacing and bounding side sheets 1 and 2 there is, preferably, a door edge-outlining frame comprising channels 9, fitted to each other and having spaced outwardly extending shouldered or Z-shaped flanges 9^a, the outer borders of which are preferably depressed.

Door sheets 1 and 2 also each have bounding flanges 1^a and contiguous shoulders, the former being secured, as by welding, to the depressed portions of the flanges 9^a of channels 9.

Paralleling the borders of the upper panel openings in said side sheets 1 and 2 there is, preferably, a panel-opening frame comprising channels 10, similar to channels 9 in form, but with their flanges 10^a inturned.

Both side sheets 1 and 2 have about their upper panel openings flanges and shoulders, conforming to those of the panel-opening frame in approximately the same relation as the door edge bounding flanges 1^a and their adjacent shoulders have to the door edge-outlining frame, and likewise the flanges of the side sheets and panel-opening frame are welded or otherwise united.

Each edge of the door, that is to say, each channel 9, is provided with a finishing strip, and each comprises an external channel member 11 and an internal flanged U-shaped channel member 12, both of which may be of equal length, though channel member 12 may comprise short pieces, and the length of the individual finishing strips correspond to the edges of the door-outlining frame to which they are applied.

The outer channel member 11 may be of drawn steel, and the free borders of its flanges are reversely bent inwardly at an acute angle to the remainder of the flanges, and the internal U-shaped channel member 12 may be a pressing of steel or other metal, and its flanges are outturned and adapted to engage with the internal surfaces of the shoulders of the Z-shaped flanges 9^a of the channel 9 of the door edge-outlining frame to which it is affixed. The closed portion of each internal U-shaped member 12 is united, as by welding or with countersunk rivets, to the web portion of the external channel member 11, resolving both channel members 11 and 12 of each strip into a unitary structure.

The individual finishing strips each has the outturned flanges of its internal channel member 12 lapping the transverse portions of the Z-shaped flanges 9^a of its associated channel 9, the outer edges of said flanges and the door-bounding flanges 1^a of side sheets 1 and 2 abut the web of the external channel member 11, and the deflected portions of the flanges of this member bear

against the said flanges of the side sheets 1 and 2 and the shoulders forming the outer edge of the stiles 3.

The finishing strips are capable of end-wise application to their respective channel members 9, and of longitudinal sliding movement therewith, having also a friction-producing fit with said channels.

Each finishing strip is arranged to have its ends so overlap the ends of adjacent finishing strips that, after being pushed into their normal positions, said finishing strips interlock with each other and become self-retaining. This interlocking of the finishing strips, however, forms subject-matter of another application filed by me on an even date herewith and entitled Metallic door with interlocking parts.

At suitable locations the channel 9, of the hinged end of the door, and the finishing strip therefor are cut away for the application of hinges. Within the zone of the cutaway portions, and preferably co-extensive with the length thereof, is inserted a reinforcement 13, best shown in Figs. 2 and 8. The cross section of each reinforcement is shown as substantially T-shaped, its stem bearing against the inner wall of channel 9 and being thick enough to fill the space between what remains of the Z-shaped flanges of said channel, i. e., the transverse portions of the channel flanges.

The cross leg of the T-shaped reinforcement bears against the shoulders of side sheets 1 and 2, and its outer surface is inset from the outer surface of outer channel member 11 of the affiliated finishing strip. Secured by screws 14 to the outer face of the cross leg of reinforcement 13, is one leaf of a hinge 15. Said cross leg of the reinforcement is preferably thick enough to cause the outer face of the hinge leaf to be in the same plane as the outer face of channel member 11 of the finishing strip.

Referring to the upper panel-opening, a molding frame is provided therefor comprising suitable pressed or otherwise formed strips 16 fitted one to the other. Preferably, each strip comprises a pair of parallel flanges adapted to lap the panel-opening outlining flanges of side sheets 1 and 2, a molding contour portion, either beveled or partaking of the lines of a classical molding, and an opening surrounding depression adapted to receive a glass or other removable panel 17 and cushioning strips 18.

The parallel flanges of each molding strip 16 lap the flanges of side sheets 1 and 2, which flanges are sufficiently depressed so that their adjacent shoulders form a second or outer depression. Within this latter depression is inserted a retaining frame comprising retaining strips 19 for the removable panel 17 and its cushioning strips 18. Said retaining strips 19 may be secured, as shown,

by screws 20, which pass through said retaining strips 19, flanges of molding strips 16 and those of sheet 1 which outline the panel-opening in said sheet, and through flanges of channel members 10 forming the panel-opening frame. It is necessary to insert the screws only from one side of the panel.

Molding strips 16 are shown as being mitered, and while not necessary, it is desirable to weld their joints transversely except for a transverse distance equal approximately to the width of the flanges of the molding strips which are adjacent the retaining strips 19. By leaving these latter flanges ununited, they may be bent to facilitate the assembling of the molding frame.

It is well known that, when applied to doors, shades or curtains are mounted to be pulled downwardly in some instances and upwardly in others, and, as for example, in relatively narrow double doors of street cars, crosswise of the door. Therefore, it is immaterial which rail or stile is selected for the application of a curtain roller. I have, however, chosen for illustrative purposes a most common location—the top rail 4 of the door.

Simulated top rail 4 of side sheet 1 is provided with a rectangular opening 21, advantageously having a length greater than the width of the upper removable panel 17, and any suitable height. Within top rail 4, which is hollow, and positioned to form a horizontally disposed concave wall is a curved sheet 22, having the curvature of a cylindrical segment. Said sheet 22 is supplied with upper and lower horizontal flanges, arranged to lap the borders of the opening 21 of side sheet 1 and adapted to be welded or otherwise secured thereto.

Closing the openings at the opposite ends of the concave sheet 22, are end pieces 23 of angular horizontal section, a vertical flange of each of which may be welded to the adjacent vertical border of opening 21 in side sheet 1. A pocket is thus formed in one side of the door for the partial reception of a shade roller and the rolled portion of the curtain or shade.

A pair of combined shade bracket and guide members are arranged one on each side of the removable panel 17, and each is preferably constructed of two parts as shown in Figs. 7 and 8, these parts preferably being fused together. The cross section through the guide portion is revealed in Fig. 8, where the inside strip 24 has a zig-zag or stepped section, and the outer strip 25 has a Z-shaped cross section, the forward inwardly-projecting flange 26 of strip 25 being rebent upon itself to abut the forwardly-extending flange 27 of the inside strip 24. The rear flange 28 of the outer Z-shaped strip 25 projects outwardly and

contacts with the face of one of stiles 3 of sheet 1.

At the rear of the forwardly-extending flange 27 of inner strip 24, said strip is bent inwardly for a distance approximating the width of the forwardly-extending flange 26 of the outer Z-shaped strip 25 to form a wall 29 parallel to the latter, thence rearwardly at right angles to the face of the stile 3, where said strip 24 is again bent inwardly to form a vertically-disposed rear flange 30. The edge of rear flange 30 may, if desired, be bent to conform to the juxtaposed shoulder of sheet 1.

In each combined bracket and guide the forward inwardly-projecting flange 26 of strip 25, the forwardly-extending flange 27 of strip 24 and the wall 29 of the latter strip, which parallels the flange 26 of strip 25, form a guideway or runway 31 for the usual runner or slide carried upon each end of the fixture which runs across the free end of the curtain or shade and is inclosed therein. The guideways 31 of both guides face each other in the usual manner, and the guides are spaced from each other in accordance with the width of the panel and the shade.

Considering the bracket portion of each combined bracket and guide, intermediate wall 29 is curved or otherwise directed rearwardly in its upper portion to continue in a convex or other manner the lower part of the concave wall portion of sheet 22, which forms, in the present instance, the pocket 100 in the top rail 4. Flange 26 of strip 25 extends above wall 29 of strip 24 and is also curved in the arc of a circle, but with a radius equal to that producing the curvature of pocket sheet 22.

An enlarged substantially circular recess merging with a guideway 31 is thus formed in the upper part of each combined bracket and guide, said recess being partly included in the pocket in the top rail 4.

Above the upper curved part of wall 29 of inside strip 24, the flange 27 of said strip is expanded to continue to fill the space between said wall 29 and the flange 26 of outer strip 25, being also backed by the web portion of the latter Z-shaped strip.

To the inner face of the expanded part of flange 27 may be secured any approved and well-known shade roller-holding brackets, or the same part of flange 27 and the part 120 of outer strip 25 which backs it may be perforated, as indicated in dot and dash lines in Figs. 3 and 6, to constitute complete bracket portions in the combined brackets and guides.

Said combined brackets and guides are preferably secured in place by screws 32 passing through both flanges 28 and 30 of each combined guide and bracket. The stile portions of side sheet 1 are furnished with

reinforcements 33 on the inner surface of said sheet, tapped to receive the threaded ends of the screws 32, which pass through flanges 28, said sheet 1 and reinforcements 33. The flanges 28 extend above the bracket portions and one of the screws 32 passes through the upper end of each of said flanges and into the top channel 9 of the door edge-outlining frame. The screws 28 passing through flange 30 are threaded into the vertical channels 10 of the panel opening outlining frame of the upper panel.

The door hereinbefore described may be economically produced, conforms to good manufacturing practice and fulfills all of the requirements for which it was designed.

Doors intended for certain uses will not require the incorporation of the door edge and panel-opening outlining frames, but when the door is intended for frequent and strenuous service, said frames are necessary to greatly prolong the life of said door.

What I claim is:

1. In a metallic door, a structure having hollow stiles and rails and a panel, a shade pocket in one of said stiles or rails, and combined shade brackets and guides arranged on opposite sides of said panel, the bracket portions thereof complementing said pocket and the guide portions being provided with shade guideways and extending away from said pocket.

2. In a metallic door, spaced and opposed door side sheets having registering panel openings, one sheet having a shade-pocket opening adjacent the panel opening, a depressed pocket-forming sheet connecting borders of the pocket opening, and combined shade-bracket and guide members of sheet metal arranged on opposite sides of the panel opening adjacent the pocket opening and formed to have guideways and attachment members, the bracket portions being alined with end portions of said pocket opening and the guide portions extending away therefrom.

3. In a metallic door having opposed side sheets with registering panel openings, one sheet containing a shade pocket, combined shade-bracket and guide members on opposite sides of one of said panel openings and connected to said pocketed sheet, the bracket portions of said members complementing portions of said pocket.

4. In a metallic door having opposite side sheets with registering panel openings, one sheet having a pocket opening, a curved pocket-forming sheet and pocket end closing pieces affixed to borders of said pocket opening, conjoined plural part combined shade-bracket and guide members of sheet metal provided with guideways and attachment members, arranged on opposite sides of the panel opening in the sheet having the pocket opening and adjacent the pocket, the

bracket portions complementing portions of the latter, reinforcement members for some of said attachment members, and means securing the latter and the reinforcement members to the pocketed door sheet.

5. In a metallic door having opposed side sheets, one sheet having a shade pocket, two-part pressed combined shade-bracket and guide members arranged on opposite sides of the panel opening in the pocketed sheet, the bracket portions complementing portions of said pocket, one part of each bracket and guide member having a Z-shaped cross section and the other a zig-zag section, both sections terminating on one side in attachment flanges and on the opposite side being bent to form guideways and merging depressed bracket portions, both member parts contacting and being united in said guideways and depressed bracket portions.

6. In a metallic door having a frame containing a shade pocket and forming a panel opening, combined shade-bracket and guide members on opposite sides of said opening, each comprising a pair of sheet metal strips having flanges attached to the frame, an edge of one strip being lapped and embraced by the contiguous edge of the other strip, said strips forming a channeled guideway and a shade-bracket portion having a recess merged with and expanding from said guideway, the bracket portions of said members complementing said pocket.

7. In a metallic frame forming an opening and having a shade pocket, combined with shade-bracket and guide members adjacent opposite sides of the opening, each comprising sheet metal strips having contacting connected portions and other flanged portions attached to the frame, said strips being bent to form a channeled guideway and a recessed bracket portion extending from and expanded beyond the guideway and provided in the bracket portion with means to support a roller end, the bracket recess forming a continuation of a portion of said shade pocket.

8. In a metallic structure, a sheet containing a panel opening and an adjacent pocket opening surrounded by the metal of said sheet, walls forming a pocket, said walls being secured to said sheet adjacent the pocket opening, shade-bracket and guide members arranged on opposite sides of the panel opening, the bracket portions having walls complementing the walls of said pocket and the guide portions containing guideways, and attachment members on said bracket and guide members secured to said sheet.

9. In a metallic structure, a sheathing having a panel opening and a pocket opening, walls receding from said sheathing adjacent the pocket opening forming a pocket having closed ends, and members extending

along opposite sides of the panel opening having shade-guide and bracket portions, and comprising depression-forming walls common to both portions, said walls in the 5 bracket portions forming a continuation of the closed pocket ends.

10. In a metallic structure, a sheathing having a panel opening and a pocket opening, a wall receding from said sheathing adjacent the pocket opening forming a pocket cavity, and members extending along opposite sides of said panel opening, each provided with a shade-guiding channel beyond which there is a shade bracket portion 15 extending into said pocket cavity and having an expanding depression communicating with said channel and pocket cavity.

11. In a metallic structure, a sheathing having a panel opening and a pocket opening, walls receding from said sheathing in proximity to said pocket opening forming a shade pocket having closed ends, and members on opposite sides of said panel opening provided with shade-guiding runways and therebeyond with expanding bracket portions, said bracket portions having shade roller supporting means and wall portions forming continuations of said closed pocket ends.

12. In a metallic structure, a sheathing having an opening, and shade guide members on opposite sides of said opening, each guide member comprising a pair of metal strips attached to and outstanding from 35 said sheathing, said strips extending away from said sheathing in spaced relation for

some distance, thereafter coming into reinforcing contact and being bent to form a shade guideway longitudinally of the associated strips.

13. In a metallic structure, a sheathing having an opening and shade members on opposite sides thereof, each guide member comprising a pair of strips having portions attached to said sheathing, said strips projecting outwardly from said sheathing in spaced relation for some distance, one strip then extending to the other, both strips, after meeting, continuing outwardly in reinforcing contact and being bent to form a shade guideway, the outer edge portions of 40 45 said contacting portions being interlocked.

14. In a metal structure, a sheathing having an opening and provided with a shade pocket, shade guide members on opposite 50 55 sides of said opening, each comprising a pair of sheet metal members attached to said sheathing and extending outwardly therefrom in spaced relation for a certain distance, then coming together, thereby forming a hollow column, said members extending outwardly from said column in reinforcing contact and being bent to form a guideway, said metal members expanding into shade bracket portions which complement 55 60 65 said shade pocket.

In witness whereof I have hereunto set my hand in the presence of two witnesses.

WALTER L. CONWELL.
